(57) **CLAIM**

The ornamental design for pair of protective covers for headphones, as shown and described.

DESCRIPTION

FIG. 1 is a front elevational view of one protective cover for headphones of a pair of protective covers for headphones showing our new design, shown separately for purposes of illustration;

FIG. 2 is a rear elevational view of our new protective cover for headphones;

FIG. 3 is a right-angled perspective view thereof;

FIG. 4 is a left-side elevational view thereof;

FIG. 5 is a right-side elevational view of the protective cover;

FIG. 6 is a left-side angled perspective view thereof;

FIG. 7 is a perspective view thereof;

FIG. 8 is a front elevational view of a second embodiment of one protective cover for headphones of a pair of protective covers for headphones showing our new design, shown separately for purposes of illustration;

FIG. 9 is a rear elevational view thereof;

FIG. 10 is a left-angled perspective view thereof;

FIG. 11 is a left-side elevational view thereof;

FIG. 12 is a right-side elevational view of the protective cover;

FIG. 13 is a left-side perspective view thereof;

FIG. 14 is a perspective view thereof;

FIG. 15 is a front elevational view of a third embodiment of one protective cover for headphones of a pair of protective covers for headphones showing our new design, shown separately for purposes of illustration;

FIG. 16 is a rear elevational view thereof;

FIG. 17 is a perspective view thereof;

FIG. 18 is a left-side elevational view thereof;

FIG. 19 is a right-side elevational view of the protective cover;

FIG. 20 is a left-side perspective view thereof;

FIG. 21 is a front perspective view thereof;

FIG. 22 is a front elevational view of a fourth embodiment of one protective cover for headphones of a pair of protective covers for headphones showing our new design, shown separately for purposes of illustration;

FIG. 23 is a rear elevational view of the headphone cover thereof;

FIG. 24 is a left-angled perspective view thereof;

FIG. 25 is a left-side elevational view thereof;

FIG. 26 is a right-side elevational view of the protective cover;

FIG. 27 is a left-side perspective view thereof; and,

FIG. 28 is a front perspective view thereof.

The broken lines form no part of the claimed design.
